UNITED STATES PATENT OFFICE.

WILLIAM M. BATEMAN, OF CHESTER, PENNSYLVANIA.

ANCHOR.

1,316,216.

Specification of Letters Patent. Patented Sept. 16, 1919.

Application filed November 25, 1918. Serial No. 263,963.

To all whom it may concern:

Be it known that I, WILLIAM M. BATEMAN, a citizen of the United States, residing at Chester, in the county of Delaware and State of Pennsylvania, have invented 5 certain new and useful Improvements in Anchors, of which the following is a specification.

My invention relates to improvements in 10 the type of anchor shown in the United States Patent No. 961,095, June 14, 1910.

One object of my present invention is to provide an anchor in which the head and connected flukes are pivotally connected 15 with the shank and to so construct the parts of my improved anchor that shearing action between the head and shank will be reduced to a minimum.

Another object is to so construct my improved anchor that the parts can be readily made and assembled.

A still further object is to so construct my improved anchor that the flukes will be provided with integral veins which are so constructed and arranged that the weighing action of the anchor will cause said veins, by engagement with the side of a ship, to be moved to move said flukes substantially into alinement with the shank.

These objects, and other advantageous ends which will be described hereinafter, I attain in the following manner, reference being had to the accompanying drawings in which

Figure 1 is a front elevation of my improved anchor,

Fig. 2 is an inverted plan view of Fig. 1,
Fig. 3 is a side view of Fig. 1,

Fig. 4 is a sectional view through the head 40 and taken on the line 4-4 of Fig. 1, the shank being omitted for clearness,

Fig. 5 is a fragmentary section through the head and taken on the line 5-5 of Fig. 3,

Fig. 6 is a fragmentary face view showing the lower end of said shank, and

Fig. 7 is a side view of Fig. 6.

Referring to the drawings, 8 represents the head of my improved anchor and is provided with lateral flukes 9. The head 8 has a cavity 10 extending upwardly from its bottom and a segmental opening 11 at its top, said segmental opening communicating with the cavity 10. The head 8 at both sides 50 of the opening 11 is undercut to provide ar-

cuate grooves 13 which communicate with the cavity 10, the grooves in cross section being smoothly rounded, as clearly shown in Fig. 5, so as to be free of any sharp edges which would start a fracture or form shearing members. Said undercut portion of the head 8 from the axes of the arcuate grooves, extending in substantially parallel arrangement in a direction away from said arcuate grooves to provide substantially parallel extensions of said grooves. The shank 14 has its extreme lower end 15 circular in longitudinal section.

Two oppositely disposed lugs 16 and 17 intercept the end 15 and flare outwardly. 70 These lugs are adapted to fit within the undercut arcuate grooves 13 of the head and a pin 18 is riveted within the head 8 and extends across the cavity 10. This pin 18 is so located between the parallel extensions of 75 the undercut grooves 13 that the curved end 15 of the shank rests and rolls thereon at all times while the lugs 16 and 17 snugly rotate within the arcuate portions of said grooves 13 and the fact that the curved end 15 of 80 the shank is curved throughout its entire width, as shown in Fig. 5, causes a good bearing surface for engagement with the pin 18. The pin 18 thus retains the shank in such position that the lugs 16 and 17 are 85 always within the undercut grooves 13. This is an important improvement of my present invention since there is practically no relative movement either in an upward or downward direction between the lugs 16 and 17 and the head 8; the only movement permitted is a pivotal movement which is limited to the extent of the width of the opening 11.

Each of the flukes 9 is provided with oppositely disposed integral veins 19 and these veins extend beyond the peripheral surface of the head, as clearly shown in Figs. 2 and 3. The outer ends of these veins engage the side of the ship during 100 the raising or lowering of the anchor and cause the flukes to be held in substantial alinement with the shank so that they will not project at an abrupt angle.

While I have described my invention as 105 taking a particular form, it will be understood that the various parts of my invention may be changed without departing from the spirit thereof, and hence I do not limit myself to the precise construction set forth, but 110

consider that I am at liberty to make such changes and alterations as fairly come within the scope of the appended claim.

Having thus described my invention, what I claim as new and desire to secure by Letters Patent is:

An anchor having a head provided with flukes and including a cavity extending upwardly from its bottom, said cavity including two oppositely disposed undercut grooves arcuate at the innermost part and having substantially parallel portions extending from said arcuate portions toward the bottom of said cavity; a pin extending across said cavity between said parallel portions of the undercut grooves; and a shank

having a portion extending through said opening into said cavity, the bottom of said shank being circular in cross section and adapted to roll throughout its entire width upon said pin, said end portion of the shank having lateral lugs fitting the arcuate portions of said undercut grooves and having their bottom portions in rolling contact with said pin; substantially as described.

In testimony whereof I have signed my name to this specification in the presence of two subscribing witnesses.

WILLIAM M. BATEMAN.
